UNITED STATES PATENT OFFICE.

LYMAN HYDE, OF ELLENVILLE, NEW YORK, ASSIGNOR TO ELLENVILLE GLASS COMPANY,
OF SAME PLACE.

MACHINE FOR FINISHING CARBOYS.

Specification of Letters Patent No. 23,063, dated February 22, 1859.

To all whom it may concern:

Be it known that I, LYMAN HYDE, of
Ellenville, in the county of Ulster and State
of New York, have invented a new and Im-
5 proved Machine for Finishing Carboys; and
I do hereby declare that the following is a
full, clear, and exact description of the
same, reference being had to the annexed
drawings, making a part of this specifica-
10 tion, in which—

Figure 1, is a longitudinal vertical section
of my invention taken in the line x, x , Fig. 3.
Fig. 2, is a transverse vertical section of
ditto taken in the line y, y , Fig. 3. Fig. 3, is
15 a plan or top view of ditto.

Similar letters of reference indicate cor-
responding parts in the several figures.

The object of this invention is to enable
heads, similar to those on the necks of bot-
20 tles and small glass vessels to be formed on
the ends of the necks of carboys and other
large glass vessels of similar or approxi-
mate form. Large vessels of this sort have
hitherto been “unfinished” as it is techni-
25 cally termed, that is to say, the ends of the
necks have been left plain without head or
“finish” in consequence of the inability of
the workman to reach the neck of the car-
boy, and perform the necessary work, the
30 finish on the vessels being hitherto done ex-
clusively by manual operation.

The within described invention consists in
connecting a treadle or lever to the ordinary
“shears” or tool by which the head is
35 formed or the work finished and having a
furnace placed in the frame of the device
and in such relation with the shears, that
while the latter are performing their work,
the carboy or vessel being operated upon,
40 will be prevented from suddenly cooling,
contracting and consequently breaking.

To enable those skilled in the art to fully
understand and construct my invention I
will proceed to describe it.

45 A, represents a rectangular frame in which
a furnace B, is placed, and C, represents the
“shears,” or forming device which molds
or gives the form to the head at the end of
the neck of the bottle. These “shears” are
50 constructed as usual, a jaw a , being on each
end of a bent spring D, and a mandrel b,
placed between the two jaws, said mandrel
being of conical form and having a collar
or stop c, at its base, see more particularly

Fig. 3. The spring D, has a tendency to 55
keep the jaws a, a , apart.

In the frame A, two upright arms E, E,
are placed, the lower ends of said arms being
connected by hinge joints d, d, to the lower
part of the frame. The upper ends of these 60
arms are attached to the jaws a, a , one to
each, and to the center of each arm E, the
ends of a strap or cord e, are secured, the
lower part of said strap being attached to
a treadle F, which has its fulcrum at f. On 65
the upper part of the frame A, and in line
with the mandrel b, of the shears two bear-
ings g, g, are placed, the use of which will
be presently explained.

The operation is as follows:—The car-
boy is formed precisely as usual, viz., by
means of the blowing tube and “marver”
and when finished it is immediately discon-
nected from the tube and a “ponty” h,
70 placed around the neck to form the head.
The ponty h, is then fitted in the bearings
g, g, of the frame A, the carboy i, shown
in red outline being over the furnace B,
and the mandrel b, being within the mouth 80
of the carboy i. The operator turns the
ponty h, in its bearings g, g, and depresses
the treadle F, with his foot, the depressing
of the treadle causing the arms E, E, to ap-
85 proach each other in consequence of the con-
nection formed by the strap or cord e, and
the jaws a, a , grasp the roll of glass around
the mouth or neck of the carboy and the
head h, will be formed thereon. The fur-
nace B, prevents the carboy from cooling 90
while the head h, is being formed.

By this invention carboys may be finished
equally as well as bottles and other small
vessels. Bottles are blown and properly
formed by the aid of the “marver” then de-
95 tached from the blowing tube a “ponty” at-
tached to its back end and the “finish”
done by hand the shears being held in the
hand and operated by them while the other
is employed in turning the “ponty” on the 10
arms of the chair. Bottles being small may
be readily manipulated, the neck of the bot-
tle being within the reach of the operator,
they also may be quickly finished so that
they are not liable to cool and crack before 10
being placed in the annealing furnace.
Carboys however being large and compara-
tively thin at the sides of their bodies are

liable to cool and crack while being finished, it is therefore necessary that they be operated upon and finished over the furnace B.

By having the shears C, arranged and connected to the treadle F, as shown, the difficulty which prevents the forming the head or finish *h*, directly by hand is obviated or not encountered.

I would remark that a box A', is placed below the shears to hold the wax with which the shears are lubricated previous to each operation.

I do not claim the "shears" or formers C, for they have been previously used; but,

Having thus described my invention, what 15 I do claim as new and desire to secure by Letters Patent, is,

The "shears" C, treadle F, or its equivalent, (mandrel *b*) and furnace B, placed within a suitable frame A, and arranged for 20 joint operation substantially as and for the purpose set forth.

LYMAN HYDE.
